RAIL SUPPORTING AND SECURING MEANS

Levi Borden Armstrong, Great Neck, N. Y., assignor to The Lundie Engineering Corporation, New York, N. Y., a corporation of New York

Application October 2, 1937, Serial No. 166,976

3 Claims. (Cl. 238—349)

The present invention relates to rail supporting and securing means. Its general object is the provision of new and improved means for properly yet resiliently holding a rail on a tie-plate and for immovably securing the latter to a rail tie.

Experience has shown that the so-called "wave motion" of a railroad rail, produced by movement of the rolling stock thereon, has a tendency to pull out of the tie the spikes by which the rail or tie-plate or both are secured to the tie, and also to lift the tie out of the ballast. By the use of devices embodying the present invention, a rail is securely yet resiliently held in engagement with the tie-plate and the latter is immovably secured to the tie, so that the wave motion of the rail is allowed to take place without producing the objectionable results above mentioned. Other advantages resulting from the use of the present invention will hereinafter be pointed out in describing the embodiments thereof which are illustrated in the drawings.

Fig. 1 is an elevation, partly in section of a rail supporting and securing means which may be regarded as a preferred embodiment of the invention; Fig. 2 is a plan view of what is shown in Fig. 1; Fig. 3 is a perspective view of the spring clip shown in Figs. 1 and 2; Fig. 4 is a section on the line 4—4 of Fig. 3 showing the cambered or convex end of said clip which engages the flange of the rail; Fig. 5 is an elevation, partly in section, similar to Fig. 1 but showing a modified form of spring clip; and Fig. 6 is a plan view of the spring clip illustrated in Fig. 5, prior to being bent into the form shown in Fig. 5. Like parts are referred to throughout the drawings by the same or similar reference characters.

Referring to Figs. 1, 2 and 5 a railway rail 8, having base flanges 9, is shown resting upon a tie-plate 10 of a well-known form having ribs 11 between which the base flanges of the rail are received. The tie-plate 10 is shown as provided with four openings therethrough, at least two of which are non-circular and preferably rectangular and pass through the ribs 11 so as to be adjacent the location of the edges of the rail flanges 9, while the other openings through the tie-plate are located nearer the edges of the tie-plate. It will be understood, however, that the number and location of the openings through the tie-plate may be varied without departing from the spirit of the invention, although it is desirable that the non-circular openings be located in the positions described. The railway tie 12, prior to impregnation with a preservative as is customary in railway practice, has holes

drilled therein at locations adapted to line up with the openings in the tie-plate, so as to facilitate attachment of the rail to the tie-plate and attachment of the tie-plate to the tie, by the means which will now be described.

In the two embodiments of the invention, illustrated in Figs. 1 to 4 and in Figs. 5 and 6 respectively, the means which holds the rail in engagement with the tie-plate includes a plurality of bolts each having a rectangular shank 15 provided with a pointed hooked or off-set end 16 of the form shown, the other end 17 of said bolt being threaded and carrying a nut 18. It will be understood from the drawings that the form of the shank portion 15 and off-set end 16 of each 15 of said bolts is such that said bolt is adapted to be inserted in one of the rectangular openings in the tie-plate, from the top side thereof, in a position inclined to said tie-plate and away from the rail, with the off-set end projecting into the hole 20 in the tie, and then to be swung into a position at right angles to the tie-plate (as shown in the drawings) with the off-set end of the bolt in engagement with the bottom of the tie-plate. In manipulating the bolts into the positions shown 25 in Figs. 1 and 5, after the off-set ends 16 have been inserted in the tie-plate, in a position inclined to the tie-plate and away from the rail as above mentioned, it is only necessary to subject the bolts to the blow of a hammer to bring them 30 into the vertical positions shown in which the pointed off-set ends of the bolts are jammed into the sides of the holes in the tie, as will be understood from Figs. 1 and 5. Therefore, no special tool is required to manipulate the bolts into the 35 position shown in the drawings. The shank portions 15 of the bolts being non-circular and preferably rectangular in cross-section, said bolts are incapable of rotation in the rectangular openings in the tie-plate when the bolts are in 40 the positions shown in Figs. 1 and 5.

In both of the embodiments of the invention herein illustrated, each bolt carries a spring clip which engages the rail flange and the top of the tie-plate. The spring clip, which is shown in side 45 elevation in Fig. 1 and in perspective in Fig. 3, has a hole 20 therein slightly larger than the threaded portion 17 of the bolt; and said clip has at one side a downwardly and inwardly bent portion 21 adapted to engage the rail flange, and 50 at the other side has a downwardly bent portion 22 adapted to engage the top of the tie-plate, in the manner shown in Fig. 1. The downwardly and inwardly bent portion 21 of the clip is of such a length that its end engages one side of the 55

rectangular shank portion 15 of the bolt, thereby preventing the clip from being rotated on the bolt either while the nut 18 is being screwed down or by the wave movement of the rail. Furthermore, 5 as best shown in Figs. 3 and 4, the downwardly and inwardly bent portion 21 of the clip has a cambered portion providing a concave surface 23 on its outside which engages the top of the rail flange 9 in a way that permits wave motion of the 10 rail without nicking or cutting of the rail flange by the edges of the clip. Thus it will be apparent that the spring clip shown in Figs. 1 to 4, in cooperation with its bolt, securely and yet resiliently holds the rail on the tie-plate 10.

15 The modified form of spring clip shown in Figs. 5 and 6 will now be described. This clip has a hole 20' therein, adapted to receive the threaded portion of the bolt, and on one side has the downwardly and inwardly bent portion 21' and on the 20 other side has the downwardly bent portion 22'. The portion 21', instead of merely abutting the shank of the bolt, is extended and is provided with a rectangular opening 24 therein of such a size that it is capable of receiving the rectangular 25 shank of the bolt. In this way, the clip is prevented from rotating on the bolt as the nut is screwed down. As will be obvious from Fig. 5, the downwardly and inwardly bent portion 21' of the clip engages the top of the rail flange 9; and the 30 downwardly bent portion 22', which is preferably of the form shown in Fig. 5, engages the top of the tie-plate 10. Thus the bolt and spring clip shown in Fig. 5 serve to securely and yet resiliently hold the rail in contact with the tie-plate.

35 It is of importance that the tie-plate be held immovably on the top of the tie. For this purpose, I have utilized the form of spike shown in Fig. 1, which has been found to be highly satisfactory. This spike has the usual head 25, but its shank 26 is characterized by the fact that one or more of the surfaces thereof is made corrugated or wavy as shown in the drawings. When such a spike is driven into the tie, preferably into a previously drilled hole therein, the expansion of the 45 wood into the wavy formations on the shank of the spike effectively prevents it from being worked out of the tie by movement of the rail as the rolling stock passes over it. Therefore, the tie-plate is immovably held in contact with the top of the tie. Thus the bolts and spring clips and the 50 particular spike which are herein described and illustrated, cooperatively serve to properly hold the rail securely and yet resiliently on the tie-plate, and to hold the tie-plate immovably on the tie, in spite of the stresses and strains to which they 55 are subjected while in use.

What is claimed is:

1. For use in holding the base flange of a rail resiliently on a tie plate, a bolt adapted to be anchored to said tie plate and having a non-cylindrical shank adapted to assume a vertical position adjacent the base flange of the rail and having a cylindrical screw-threaded upper end, a spring clip having a hole therein adapted to receive the screw-threaded end of said bolt and having at one side a downwardly and inwardly bent portion adapted to engage the rail flange and provided with an edge shaped to continuously contact and to assume substantially abutting engagement with a portion of the surface of the 70

non-cylindrical shank of said bolt whereby the clamp is held against turning with relation to said bolt, said clamp having on its other side a downwardly bent portion adapted to engage the tie plate at a substantial distance from the point at which said downwardly and inwardly bent portion is adapted to engage the rail flange, and a nut adapted to be run down on the screw-threaded end of said bolt and to engage the clamp intermediate its ends and to flex the same longitudinally of said bolt toward the non-cylindrical shank thereof whereby the clamp may be placed under tension while engaging the tie plate and the base flange of the rail.

2. For use in holding the base flange of a rail 15 resiliently on a tie plate, a bolt adapted to be anchored to said tie plate and having a non-cylindrical shank adapted to assume a vertical position adjacent the base flange of the rail and having a cylindrical screw-threaded upper end, a 20 spring clip having a hole therein adapted to receive the screw-threaded end of said bolt and having at one side a downwardly and inwardly bent portion presenting a convex surface adapted to engage the rail flange and provided with an 25 edge shaped to continuously contact and to assume substantially abutting engagement with a portion of the surface of the non-cylindrical shank of said bolt whereby the clamp is held against turning with relation to said bolt, said 30 clamp having on its other side a downwardly bent portion adapted to engage the tie plate at a substantial distance from the point at which said downwardly and inwardly bent portion is adapted 35 to engage the rail flange, and a nut adapted to be run down on the screw-threaded end of said bolt and to engage the clamp intermediate its ends and to flex the same longitudinally of said bolt toward the non-cylindrical shank thereof whereby the clamp may be placed under tension while engaging the tie plate and the base flange of the rail.

3. For use in holding the base flange of a rail 45 resiliently on a tie plate, a bolt adapted to be anchored to said tie plate and having a non-cylindrical shank adapted to assume a vertical position adjacent the base flange of the rail and having a cylindrical screw-threaded upper end, a 50 spring clip having a hole therein adapted to receive the screw-threaded end of said bolt and having at one side a downwardly and inwardly bent portion adapted to engage the rail flange and provided with an opening conforming substantially to the cross-sectional contour of the 55 non-cylindrical shank of said bolt and adapted to receive such shank whereby the clamp is held against turning with relation to said bolt, said clamp having on its other side a downwardly bent portion adapted to engage the tie plate at a substantial distance from the point at which said 60 downwardly and inwardly bent portion is adapted to engage the rail flange, and a nut adapted to be run down on the screw-threaded end of said bolt and to engage the clamp intermediate its ends and to flex the same longitudinally of said bolt toward the 65 non-cylindrical shank thereof whereby the clamp may be placed under tension while engaging the tie plate and the base flange of the rail.
